UNITED STATES PATENT OFFICE.

FRANK B. GRANGER, OF NEW YORK, N. Y., ASSIGNOR TO HALL-BORCHERT DRESS FORM COMPANY, OF NEW YORK, N. Y., A CORPORATION OF NEW JERSEY.

DRESS-FORM.

1,286,879.

Specification of Letters Patent.

Patented Dec. 3, 1918.

Application filed June 14, 1915. Serial No. 33,879.

To all whom it may concern:

Be it known that I, FRANK B. GRANGER, a citizen of the United States, residing at New York, county of New York, State of New York, have invented an Improvement in Dress-Forms, of which the following description, in connection with the accompanying drawing, is a specification, like characters on the drawing representing like parts.

10 This invention relates to dress forms and involves a novel skirt form endwise collapsible and circumferentially extensible. One of the main objects of my invention is to so construct and connect the parts of the skirt form that all of the substantially vertical members thereof constitute components of the same curved surface, whether extended or collapsed, whereby a smooth exterior surface is presented.

20 In order to give an understanding of the invention, I have illustrated in the drawings a selected embodiment thereof which will now be described, after which the novel features will be pointed out in the appended claims.

In the drawings, Figure 1 is a front view of a dress form provided with my improved skirt portion;

Fig. 2 is a view showing the skirt portion collapsed;

Fig. 3 is an enlarged section on the line *x*—*x*, Fig. 1;

Fig. 4 is a section on the line *y*—*y*, Fig. 1;

Fig. 5 is a section on the line *a*—*a*, Fig. 1;

Fig. 6 is a detail of the adjustable arm for holding the lower hoop or band;

Fig. 7 is a bottom plan view of the skirt portion;

Fig. 8 is a section on the line *b*—*b*, Fig. 6;

Fig. 9 is a detail of the plate 32.

1 designates the body portion of a dress form which is herein illustrated as divided into a plurality of sections, and 2 indicates generally the skirt portion of the form.

45 This skirt portion has a telescopic construction so that it can be folded or extended. The dress form is supported on a suitable standard shown generally at 3 which will preferably be of the collapsible or telescopic variety, such, for instance, as is shown in my co-pending application Se. No. 8082, filed February 13, 1915, but which it is not necessary to describe in detail herein as it forms no part of the present invention. A

supporting standard of this nature can be 55 collapsed so as to allow the dress form to be lowered into the position shown in Fig. 2, thus providing for reducing the space occupied by the form when the latter is to be shipped or stored.

To permit the dress form to be thus lowered necessitates a folding skirt portion, and the improved skirt portion forming the basis of this application is one in which the folding thereof is accomplished by a telescopic 60 action. The skirt section herein shown comprises a plurality of annular sections having a telescopic relation to each other which permits the necessary folding action thereof. These sections will preferably be made 65 expandible so as to permit the size of the skirt portion to be varied circumferentially. In the construction shown in the drawings the skirt portion is made of three annular sections, the upper section being indicated 70 at 4 and being secured at its upper end to the body portion 1, the intermediate section being indicated at 5 and the lower section at 6.

The telescopic construction for the annular sections may be provided for in various ways without departing from the invention. Where the dress form is an adjustable dress form and is divided vertically to present a plurality of hip sections 7, I propose 80 to divide the skirt portion into sections, one for each of the hip sections and to connect said sections to permit the skirt portion to be expanded or contracted in diameter. This is the construction illustrated in the 85 drawing, and the sections of the skirt portion formed by the vertical division thereof are indicated generally at 8. Each of these sections comprises the upper element 9, the intermediate element 10, and the lower element 11, said three elements forming part 90 of the upper, intermediate and lower annular skirt sections 4, 5 and 6, and having a telescopic relation with each other. One convenient way of providing for this is to 100 make the upper element 9 with the two members 12 which are secured at their upper end to a hip section 7 and are shown as connected by a cross strip 13, said side members 12 each having a guiding loop 14 at its lower 105 end, and to make the intermediate element 10 with the two side members 15 which slide through the guiding loops 14 and are con-

nected at their upper and lower ends by cross pieces 16 and 17, the upper cross pieces 16 having loops 18 at their ends which slide on the side members 12 of the upper member, and said intermediate member having the central guiding member 19 connecting the upper and lower cross pieces 16 and 17; and to make the lower element 11 with the two side pieces 20 which are slidably mounted on the central member 19 of the intermediate element. The upper ends of the members 20 are connected by two cross pieces 21 which are situated on opposite sides of the central member 19 and thus form a guiding aperture through which said member extends. The lower cross piece 17 of the intermediate element is formed by two pieces between which the members 20 extend. Each set of assembled upper, intermediate and lower elements 9, 10 and 11 constitutes a telescopic or collapsible skirt-portion unit. These skirt-portion units are flexibly connected together by folding connecting members 22, each comprising two links 22 pivotally connected together at 23 and pivotally connected to the adjacent skirt portion units at 24. The lower ends of the skirt-section units are all connected to a hoop or band 25 at the bottom of the skirt portion which is herein shown as made of a plurality of links 26 pivotally connected together to form a lazy-tongs construction, thus providing an expandible and collapsible member.

This lower member 25 is also adjustably connected to the central standard 3 by means which holds it properly positioned. This adjustable connection is shown as a collar 27 mounted freely on the standard and having extending therefrom extensible radially-arranged arms 28 which are connected at their outer ends to the band 25. These arms are each herein shown as comprising the member 29 connected to the collar, the member 30 pivotally connected to the band 25 at 31, and the intermediate member 32 having slots 33, 34 therein in which operate clamping screws 35, 36 carried by the two members 29 and 30. These members 29 and 30 are shown as provided with the slots 360 which embrace studs or guiding projections 37 carried by the intermediate member 32. This makes an extensible connection which, however, is rigid in a vertical direction and firmly holds the skirt section in its adjusted position. I will preferably make the upper, intermediate and lower elements of each unit of flat metal strips as this provides a skirt portion having a smooth exterior which is well adapted to act as a support for skirts.

It will be noted that in the construction herein shown the various elements of each telescopic section are in vertical alinement with each other, that is, the two side mem-

bers 12 of the upper element, the two side members 15 of the intermediate element, and the two members 20 of the lower element, are all vertical components of the same curved surface whether the skirt be collapsed or extended. The advantage of this construction is that the skirt portion presents a smooth exterior surface.

I claim:

1. A skirt form, including a plurality of annular sections, each including a plurality of longitudinally extending members and retaining and guiding members, said retaining and guiding members being positioned at each end of each section except at the upper end of the upper section and the lower end of the lower section and serving to retain all of said longitudinal members in the same vertical substantially cylindrical surface during an endwise extension or collapsing of the form.

2. A skirt form, including a plurality of annular sections, including an upper section, a lower section and an intermediate section, each of said sections including a plurality of longitudinally extending members, the members of the intermediate section having guiding means at each end thereof slidable along the longitudinal members of the upper and lower sections and the upper and lower sections having guiding means at their lower and upper ends respectively slidable along the longitudinal members of the intermediate section during the endwise extension or collapsing of the form.

3. A skirt form, divided horizontally into a plurality of skeleton elements, each element including longitudinal members and transverse members at the ends thereof, said transverse members of each element having guided sliding relationship with the longitudinal members of the adjacent elements whereby the ends of all of the longitudinal elements are held together when the form is collapsed endwise.

4. In a dress form, the combination with a body portion, of a skirt portion divided vertically to present a plurality of vertically-extensible sections, each of which is composed of a plurality of elements situated in vertical alinement with each other and having a telescopic relation with each other, each element presenting two connected vertically-extending members, all of the members of each section being disposed in the same vertical surface of curvature.

5. In a dress form, the combination with a body portion, of a skirt portion divided vertically to present a plurality of vertically-extensible sections, each of which is composed of an upper, an intermediate, and a lower element, and each of which presents two connected vertically-extending members, the members of the lower element being situated between the members of the interme-

diate element, and those of the intermediate element between the members of the upper element.

6. In a dress form, the combination with
5 a body portion, of a skirt portion divided
vertically to present a plurality of sections,
each of which is composed of an upper ele-
ment, an intermediate element, and a lower
element, each upper element having two con-
10 nected vertically-extending members pro-
vided with loops at their lower ends, each in-
termediate member also presenting two ver-
tically-extending members slidably mounted
through said loops and connected at their
15 lower ends by cross pieces, and each lower
element presenting two vertically-extending
members slidably mounted in the cross pieces
for the intermediate element, said elements
having a telescopic relation.

7. A skirt form including a plurality of 20
annular sections of skeleton form each in-
cluding a plurality of substantially vertical
members, and connections between said sec-
tions permitting the relative endwise move-
ment of said members and retaining them in 25
the same substantially cylindrical surface to
vary the length of said skirt portion.

8. A skirt form including a plurality of
sections, each including a plurality of sub-
stantially vertical members, and means be-
tween said members for positively holding
the adjacent ends of all members against
relative radial movement during the relative
endwise movement in extending or collaps-
ing the skirt form.

In testimony whereof, I have signed my
name to this specification.

FRANK B. GRANGER.
